US00D824019S

(12) **United States Design Patent** (10) **Patent No.:** **US D824,019 S**
Warby et al. (45) **Date of Patent:** **** Jul. 24, 2018**

(54) **INHALER**

- (71) Applicant: **Consort Medical plc**, Hemel Hempstead, Hertfordshire (GB)
- (72) Inventors: **Richard Warby**, Wisbech (GB); **Carol Balfour**, King's Lynn (GB)
- (73) Assignee: **Consort Medical plc** (GB)
- (**) Term: **15 Years**
- (21) Appl. No.: **29/584,326**
- (22) Filed: **Nov. 14, 2016**

(30) **Foreign Application Priority Data**

- Jun. 22, 2016 (EP) 003232859

(57) **CLAIM**

The ornamental design for an inhaler, as shown and described.

DESCRIPTION

FIG. 1 is a perspective view of an inhaler showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof;

FIG. 8 is a perspective view of a second embodiment thereof;

FIG. 9 is a front elevational view thereof;

FIG. 10 is a rear elevational view thereof;

FIG. 11 is a top plan view thereof;

FIG. 12 is a bottom plan view thereof;

FIG. 13 is a left side elevational view thereof; and,

FIG. 14 is a right side elevational view thereof.

The broken lines in the drawings depict portions of the inhaler that form no part of the claimed design.

(Continued)

The drawings include CAD lines that indicate contour, not surface decoration.

1 Claim, 14 Drawing Sheets
